CLAIM

The ornamental design for [a] an enclosure [skirt] for a peritoneal dialysis device, as shown and described.

DESCRIPTION

FIG. 1 is a front, top, and right side perspective view of the enclosure [skirt] for a peritoneal dialysis device, showing the new design;

FIG. 2 is a front side elevational view thereof;

FIG. 3 is a rear side elevational view thereof;

FIG. 4 is a right side elevational view thereof [ ];

FIG. 5 is a left side elevational view thereof; [and]

FIG. 6 is a top plan view thereof; and,

FIG. 7 is a bottom plan view thereof.

The broken lines *immediately adjacent the shaded areas* represent [unclaimed portions of the enclosure skirt for a peritoneal dialysis device and] *the bounds of the claimed design while all other broken lines are directed to environment and are for illustrative purposes only; the broken lines form no part of the claimed design.*

1 Claim, 6 Drawing Sheets

Matter enclosed in heavy brackets [ ] appears in the original patent but forms no part of this reissue; matter printed in italics indicates the additions made by reissue.
